UNITED STATES PATENT OFFICE.

WILLIAM HOWARD EDWARDS, OF GRAND RAPIDS, MICHIGAN.

LOOSE-LEAF BOOK.

1,270,713.

Specification of Letters Patent. Patented June 25, 1918.

Application filed July 9, 1915. Serial No. 38,887.

To all whom it may concern:

Be it known that I, WILLIAM HOWARD EDWARDS, a citizen of the United States, residing at Grand Rapids, in the county of 5 Kent and State of Michigan, have invented new and useful Improvements in Loose-Leaf Books, of which the following is a specification.

This invention relates to loose leaf books 10 and consists in certain improvements in the construction thereof as will be hereinafter fully described and pointed out in the claims.

With leaves for loose leaf books it is desirable to have the hinge portion softened 15 so that the paper will make a more abrupt turn at the hinge and thus permit the leaf as a whole in the book to lie more flat. It is also desirable to provide a portion of the leaf with a swell so as to better secure the leaves in the book and to assist in the 20 cooperation of the parts forming the book. The object of this invention is to improve loose leaf books and leaves therefor as to 25 these features. Other objects of the invention will appear from the specification and claims.

The invention is illustrated in the accompanying drawings as follows:

30 Fig. 1 shows a plan view of a leaf.

Fig. 2 an end view of a leaf showing the creases, the first step in softening the hinge portion.

Fig. 3 an end view showing the creases reversed, the second step in softening the hinge portion.

Fig. 4 an end view with the softened portions ironed out and the leaf provided with corrugations forming a swell.

40 Fig. 5 a section on the line 5—5 in Fig. 6.

Fig. 6 a transverse section through one of the binding elements on the line 6—6 in Fig. 5, the book being closed.

Fig. 7 a section similar to the section 45 shown in Fig. 6, the book being open.

1 marks the leaf. This has along the hinge portion parallel strips or ribbons 2 and 3 which are softened with an intervening portion 4 of solid paper.

50 In forming the softened portions I first crease the paper lengthwise of the grain of

the paper, such creases being parallel and alternating so as to form a corrugation. The end view of the paper as it comes from the first creasing is shown in Fig. 2, the creases being marked 3^a. I then reverse these creases preferably in the same machine and by a successive pair of rolls so that the creases will take the form shown in Fig. 3. It will be observed that the paper along each crease will have been bent in opposite directions thus thoroughly softening the paper without removing any portion of it. After creasing the paper in this manner and reversing the creases I then preferably flatten the paper by ironing, making the softened strips 2 and 3. This is also preferably done in the same machine, the three operations being successive. The softened portions are practically of the same thickness 60 as the other part of the leaf but the softened portions bend very much more readily.

In forming the softened portions at intervals with an intervening portion of solid paper as 4, the leaves take a sharp bend or 65 bends in the book and thus more completely assume the desired flat position in the book when open. The curve is sharpest in the softened portions but less sharp in the intervening portion 4 so that there is an irregular curve formed when the book is open. This gives to the leaf a flatter face than where there is a uniform curve or one formed by uniform resistance to flexure. The interposing of the solid portions also facilitates the creasing and ironing actions in 70 that these intervening portions assist in holding the leaf in shape during these operations and also prevents a tendency to wrinkle in the softened portion, this tendency being present where an unbroken wide softened strip is used.

The creasing not only breaks but stretches the paper and better results are accomplished by creasing lengthwise of the grain of the 75 paper in that in this instance there is in a way a separation of the fiber as distinguished from an actual breaking of the fiber.

I prefer to provide the sheets with a 100 swelled or thickened portion 5. This may be formed by a series of corrugations or creases.

With the corrugations nested and the crests in register there is a slight swelling of the leaf body. In the actual book as closed or open these corrugations or creases are slightly 5 out of register thus making a material increase in the thickness of the book in these portions.

In Figs. 5, 6 and 7 there is shown a loose leaf book in which the leaves as shown in 10 Figs. 1 to 4 are used. In these 6 marks the covers and 7 the leaf holding bands. These are preferably steel springs and operate in the general manner of the steel springs described in the patents issued to William S. 15 Proudfoot, #1,037,314 and #1,037,315. The springs are retained in the inner face of the cover 6, being held by strips 8, the covers having an edge 9 extending beyond the strips 8 forming what is commonly called 20 an extension edge, the result being to have the steel springs leave the covers on their inner faces slightly away from the edges of the covers. A spring back 10 is provided being hinged at 11 to the covers. 25 In the operation of books thus formed, the steel springs form arches when the book is closed, as clearly shown in Fig. 6, each of which arches extends to the rear of the binding edges. This arching of the springs also 30 moves the leaves of the book so that a large part of the swelled portion 5 is to the rear of a line between the binding edges. It also carries the corrugations in the leaves slightly out of register thus making the leaf body 35 slightly thicker. The result is that the rear edges of the leaves are fanned out as clearly shown in Fig. 6 and this results in a better securing of the leaves and a tendency to make a more even and extended arch of the 40 steel bands. This thickening of the leaf body also has a tendency to operate against the binding edges to more certainly hold the covers in closed position because the thicker portion of the leaf body operating on the 45 extension edges is to the rear of the point where the springs leave the face of the covers and the effect is to spread the extension edges and swing the forward portions of the covers toward each other. When the 50 book is open these swelled portions are also moved out of register to the front of a line between the edges and this increases the thickness at this point and tends to compensate for the straightening out of the arch and thus assists in holding the leaves in 55 place. It also tends to thrust the opening point of the leaf body upward so that the leaf body extending from the opening portion as shown in Fig. 7 lies more flat.

60 What I claim as new is:—

1. A leaf for loose leaf books having the hinge portions softened by creasing with a plurality of alternating creasings lengthwise of the grain of the paper and parallel to the hinge edge which creases have been reversed.

2. A leaf for loose leaf books having the hinge portions softened by creasing with a plurality of alternating creasings lengthwise of the grain of the paper and parallel to the hinge edge which creases have been 70 reversed and flattened.

3. In a loose leaf book, the combination of covers; resilient leaf holding elements extending between the covers; and a loose leaf body, the leaves of which have protuberances adjacent to the leaf holding elements, said protuberances being nested and in register when the edges of the leaves are in alinement perpendicularly to the faces of the leaves, and moving into and out of register as the leaf holding elements are flexed in the operation of the book, producing an increased thickness in the leaf body. 80

4. In a loose leaf book, the combination of covers; resilient leaf holding elements extending between the covers; and a leaf body carried by the book, the leaves of which have protuberances which are nested and in register when the edges of the leaves are in alinement perpendicularly to the faces of the leaves, said leaf holding elements being deflected upwardly with the book open and moving the front and rear edges of the leaves out of alinement and the protuberances out of register. 90

5. In a loose leaf book, the combination of covers; resilient leaf holding elements extending between the covers; and a leaf body carried by the book, the leaves of which have protuberances which are nested and in register when the edges of the leaves are in alinement perpendicularly to the faces of the leaves, said leaf holding elements forming a rearward arch with the book closed and moving the front and rear edges of the 100 leaves out of alinement and the protuberances out of register. 105

6. In a loose leaf book, the combination of covers; leaf holding springs extending between the covers and adapted to extend to 110 the rear of the binding edges of the covers when the covers are closed; and a leaf body having a swell adjacent to and in front of said springs, said swell extending to the rear of the edges of the covers with the book closed and forming an increased thickness of the leaf body to the rear of the edges of the covers. 115

7. In a loose leaf book, the combination of covers; leaf holding springs extending between the covers and adapted to arch to the rear of the edges of the covers with the book closed and to oppositely arch with the book open; and a leaf body, the leaves of which have a swell adjacent to and in front of said springs, said swell being carried into an arched position to the rear when the book is closed and in the opposite direction with the book open. 125

8. In a loose leaf book, the combination 130

of covers; resilient leaf holding elements extending between the covers and adapted to be deflected upwardly as the book is opened; and a leaf body, the leaves of which have a 5 swell adjacent to and in front of said elements and strips along the hinge portion and in front of the swell softened.

Copies of this patent may be obtained for five cents each, by addressing the "Commissioner of Patents, Washington, D. C."

In testimony whereof I have hereunto set my hand in the presence of two subscribing witnesses.

WILLIAM HOWARD EDWARDS.
